(57) **CLAIM**

We claim the ornamental design for a utensil shaft, as shown and described.

DESCRIPTION

FIG. 1 is a top perspective view of a utensil shaft showing our new design;

FIG. 2 is a top plan view thereof;

FIG. 3 is right side elevational view thereof, the left side elevational view being a mirror image of the right side elevational view shown;

FIG. 4 is a bottom plan view thereof;

FIG. 5 is a front elevational view thereof; and,

FIG. 6 is a rear elevational view thereof.

The ornamental design which is claimed is shown in solid lines in the drawings. The broken lines in the drawings are for illustrative purposes only and form no part of the claimed design.
